WILLIAM J. EVERETT, OF INDIANAPOLIS, INDIANA.

FEED-WATER HEATER AND PURIFIER FOR BOILERS.

1,276,339.

Specification of Letters Patent. Patented Aug. 20, 1918.

Application filed December 3, 1915. Serial No. 64,837.

To all whom it may concern:

Be it known that I, WILLIAM J. EVERETT, a citizen of the United States, residing at Indianapolis, in the county of Marion and State of Indiana, have invented a new and useful Feed-Water Heater and Purifier for Boilers, of which the following is a specification.

The object of my invention is to produce a simple, yet exceedingly efficient, device for automatically purifying the feed water for boilers by means of which impurities precipitable by rapid heating of the feed water may be removed.

15 The accompanying drawing shows my device in vertical section as attached to an ordinary steam boiler.

In the drawing, 10 indicates a boiler from which leads a pipe 11, said pipe being provided with a valve 12 and delivering into the side of a fitting 13. Leading downwardly from fitting 13 is a pipe 14 which should be considerably larger than pipe 11. Fitting 13 is provided with a downwardly projecting nozzle 15 which is preferably arranged centrally of pipe 14 and projects down beyond pipe 11. Leading into nozzle 15 is a feed water supply pipe 16 provided with a suitable valve 17. Pipe 14 leads into a head 18 of a settling drum 19 which, at its lower end, is provided with a head 20 from which leads a sludge pipe 21, provided with a suitable valve 22. Drum 19 may be conveniently formed of a short section of standard pipe of considerably larger diameter than pipe 14 and leading from the upper end of the drum, conveniently from the side of head 18, is a pipe 23 which leads into the lower part of boiler 10 and is provided with a suitable valve 24. The mouth of pipe 23 is guarded from pipe 14 by a guard 25 which preferably extends below the level of pipe 23.

40 The nozzle 15 is a spraying nozzle, so that it produces streams smaller than pipe 14 and, in order that pipes 23 and 11 be straight, it is desirable that the drum 19 be arranged below the level of the boiler.

In operation, the hot water from the boiler flows through pipe 11 into fitting 13, where it surrounds nozzle 15 and quite suddenly heats the incoming feed water so as to precipitate the impurities. When the treated water reaches the drum 19, the precipitate settles to the bottom, the outflow being at 45 considerably reduced velocity, owing to the

size of pipe 23, and the pure water flows through pipe 23 into the boiler.

I have found, in the practical use of this device, that ordinary hard waters, such, for instance, as those furnished by wells and streams in the vicinity of Indianapolis, Indiana, yield quite readily to treatment in the apparatus which I have described, and that practically all boiler-injuring impurities are removed. The drum 19 may be of any desired capacity, but most conveniently it may be of such size that the sludge should be removed once or twice a day by opening valve 22.

70 I claim as my invention:

1. In a feed water purifier, the combination with a boiler, of a relatively long and substantially vertical mixing tube, a supply pipe arranged below the water level in the boiler and connecting said boiler and the upper end of the mixing tube, a feed-water nozzle leading into the upper end of said mixing tube and delivering below the mouth of the supply pipe, the mixing tube being materially larger than the nozzle, a drum into which the lower end of the mixing tube opens directly downward, said drum being materially larger than the mixing tube, a sludge discharge at the lower end of said drum, said drum being free from obstructions below the open lower end of said mixing tube and said sludge discharge so that any sediment may settle from the mixing tube through the drum into said sludge discharge without interference, and a pipe connecting 75 the upper portion of said drum with the boiler at a point below the supply pipe.

80 2. As an article of manufacture, a feed water heater and purifier comprising a settling drum having a sludge discharge, an outlet leading from the upper end of said drum, a bottomless mixing tube opening at the bottom directly into the upper end of said drum, said mixing tube being relatively long and of materially less diameter than 85 the drum, and said drum being free from obstructions below the open lower end of said mixing tube and said sludge discharge so that any sediment may settle from the mixing tube through the drum into said sludge discharge without interference, a water supply inlet at the upper end of said mixing tube, and a feed-water nozzle leading into the upper end of said mixing tube below the water supply inlet, said nozzle 90

110

being of materially less diameter than the mixing tube and supply inlet.

3. As an article of manufacture, a feed water heater and purifier comprising a settling drum having a sludge discharge, an outlet leading from the upper end of said drum, a bottomless mixing tube opening at the bottom directly into the upper end of said drum, said mixing tube being relatively long and of materially less diameter than the drum, and said drum being free from obstructions below the open lower end of said mixing tube and said sludge discharge so that any sediment may settle from the mixing

tube through the drum into said sludge discharge without interference, a water supply inlet at the upper end of said mixing tube, and a feed-water nozzle leading into the upper end of said mixing tube below the water supply inlet, said nozzle being a spraying nozzle of materially less diameter than the mixing tube and supply inlet. 15 20

In witness whereof, I have hereunto set my hand at Indianapolis, Indiana, this 1st day of December, A. D. one thousand nine hundred and fifteen.

WILLIAM J. EVERETT.
